CLAIM

The ornamental design for a hat rack, as shown and
described.

DESCRIPTION

FIG. 1 is a side elevational of the hat rack showing my new design, all sides being identical, the cord being broken away to indicate indeterminate length, and the broken lines being shown for illustrative purposes only; FIG. 2 is a side elevational view of the supporting clip shown separately for clarity of illustration;

FIG. 3 is a top plan view of FIG. 2;

FIG. 4 is a rear elevational view of FIG. 4;

FIG. 5 is a partial sectional view taken in the direction of the arrows on line 5—5 of FIG. 1; and,

FIG. 6 is a side elevational view of a second embodiment of the design of FIG. 1, the only difference being the mounting structure.
